[57] **CLAIM**

The ornamental design for an ink dauber, as shown.

DESCRIPTION

FIG. 1 is a perspective view of an ink dauber showing my new design;

FIG. 2 is a top plan view thereof;

FIG. 3 is a front elevational view thereof;

FIG. 4 is a right side elevational view thereof which is the mirror image of the left side;

FIG. 5 is a rear elevational view thereof;

FIG. 6 is a bottom plan view thereof;

FIG. 7 is a perspective view of a second embodiment of FIG. 1;

FIG. 8 is a top plan view of FIG. 7;

FIG. 9 is a perspective view of a third embodiment of FIG. 1;

FIG. 10 is a top plan view of FIG. 9;

FIG. 11 is a perspective view of a fourth embodiment of FIG. 1;

FIG. 12 is a top plan view of FIG. 11;

FIG. 13 is a perspective view of a fifth embodiment of FIG. 1; and

FIG. 14 is a top plan view of FIG. 13.

The broken lines in FIG. 1 are for purposes of illustration only and form no part of the claimed design.

FIG. 1FIG. 2FIG. 3FIG. 4FIG. 5FIG. 6FIG. 7FIG. 8FIG. 9FIG. 10FIG. 11FIG. 12FIG. 13FIG. 14
